I. POWERS.

SMOKE GENERATOR FOR SMOKING MEATS.

APPLICATION FILED NOV. 5, 1917.

1,273,535.

Patented July 23, 1918.

Inventor
Isaac Powers

By his Attorney

Henry J. Lucke

UNITED STATES PATENT OFFICE.

ISAAC POWERS, OF TERRE HAUTE, INDIANA.

SMOKE-GENERATOR FOR SMOKING MEATS.

1,273,535.

Specification of Letters Patent. Patented July 23, 1918.

Application filed November 5, 1917. Serial No. 200,275.

To all whom it may concern:

Be it known that I, ISAAC POWERS, a citizen of the United States of America, residing at Terre Haute, county of Vigo, State of

5 Indiana, 1535 South Center street, Terre Haute, Ind., have invented certain new and useful Improvements in Smoke-Generators for Smoking Meats, of which the following is a specification.

10 This invention relates to smoke generators for smoking meats, and particularly to smoke generator equipments of the gas-fired type.

More particularly the invention, in its 15 preferred forms, comprises a frame constructed to be positioned within a smoke-house or other suitable inclosure, said frame being of the open-bottom type adapted to contain saw dust or the like and effect the 20 desired smoking of the meats suspended or otherwise placed within such inclosure. Suitable priming or initial ignition means is arranged in proper relation to the frame, as will be understood.

25 The generator is preferably operated by the utilization of saw dust, which is slowly ignited to produce the desired degree of smoke concomitant with ignition.

Further features and objects of the invention will be more fully understood from 30 the following description and the accompanying drawings, in which—

Figure 1 is a vertical section of a smoke-house provided with a smoke generator;

35 Fig. 2 is a side elevation of the smoke generator, Fig. 1; and

Fig. 3 is a top plan view of Fig. 2 but having a portion of the canopy broken away.

Referring to the drawings, the smoke-house is indicated diagrammatically at 1, said smoke-house being of any desired form 40 of internal contour and preferably of the type having an ash pit of any approved construction.

45 The smoke generator may be described generally as a frame or open bottom container constructed to be positioned within the ash pit of the smoke-house 1. The generator as shown is especially constructed for

50 the utilization of saw dust or like combustive material having a high content of volatile carbonaceous ingredients capable of effecting the desired "curing" of meats as is understood in the art.

55 The saw dust or the like is indicated at 3, and may be placed within the container by

pouring the same through the open top 4, whereupon the saw dust 3 flows through the open bottom 5 onto the bottom 6 of the smoke-house 1 or fire pit. 60

The container 2 comprises preferably the oppositely disposed side plates 7, 7 and the oppositely disposed end plates 8, 8. The container 2 may be of an elongated rectangular shape as shown, the particular shape, 65 however, being determined by the particular interior construction of the smoke-house 1.

The container 2 is shown supported by the legs 9, such as L-bars, which may also serve 70 to connect the abutting joints of the side plates 7 and end plates 8 as indicated in the drawings.

75 Preferably, a canopy 10 is employed and adapted to normally project above the container 2 to prevent drippings of the meat from dropping within the frame 2 or into the fire pit 6. It is convenient to construct the canopy 10 of the pivotal type as by pivoting the same to one side 11, and to 80 provide the counterweight 12 attached by means of the flexible rope 13 to the eyes 14, on the canopy 10, to facilitate removing the canopy when desiring to fill the container with saw dust or on other occasions. 85

I have shown the container 2 provided with the burners 15 suitably connected with a supply of ignition gas for the purpose of starting the combustion of the saw dust or the like. The ignition zone of the pile of 90 saw dust is disposed substantially below the frame 2. The burners 15 are shown having their burner openings 16 all directed toward that portion of the pile of combustible material disposed below the sides of the 95 frame 2.

100 Preferably, I also provide the air pipes 17, 17, having one or more sets of jet openings 18 directed toward various portions of the pile of saw dust.

The oppositely disposed baffle plates 20, 20, are provided to intensify the ignition effect of the flames projected from the burners 15 and to also intensify the injection of the air projected by the pipes 17. 105

The legs 9 may be extended upwardly as indicated by 19, to provide a rest for the canopy 10 when in normal position.

The pilot burner 21 may be provided to facilitate the starting of the gas burners 110 15, 15.

The frame 2, legs 9, extensions 19 and

baffle plates 20 may be formed of steel, or other plate metal or similar rigid material capable of withstanding the temperature and products of combustion evolved upon 5 the combustion of the fuel.

Further modifications and changes may be made without departing from the scope of the invention as defined by the appended claims.

10 I claim.

1. A smoke generator for smoking meats comprising the combination with an inclosure for the meats, of a frame having an open bottom adapted to contain saw dust or 15 the like.

2. A smoke generator for smoking meats, comprising the combination with an inclosure for the meats, of a frame having an open bottom adapted to contain saw dust 20 and means for preliminarily igniting said saw dust or like fuel.

3. A smoke generator for smoking meats comprising the combination with an inclosure for the meats, of a frame having an 25 open bottom adapted to contain saw dust or the like, and means for supplying air to said fuel.

4. A smoke generator for smoking meats comprising the combination with an inclosure for the meats, of a frame having an 30 open bottom adapted to contain saw dust or the like, means for preliminarily igniting said fuel and means for supplying air to said fuel.

35 5. A smoke generator for smoking meats comprising the combination with an inclosure for the meats, of a frame having an open bottom adapted to contain saw dust or the like and a canopy disposed above 40 said frame.

6. A smoke generator for smoking meats comprising the combination with an inclosure for the meats, of a frame for containing saw dust or like fuel, said frame com-

prising side and end plates and legs for 45 supporting said frame above the floor of said inclosure.

7. A smoke generator for smoking meats comprising the combination with an inclosure for the meats, of a frame for containing saw dust or like fuel, said frame comprising side and end plates, legs for supporting said frame above the floor of said inclosure, means for supplying air to said fuel and baffle means for directing the supplied air toward the bottom of said frame. 50 55

8. A smoke generator for smoking meats comprising the combination with an inclosure for the meats, of a frame for containing saw dust or like fuel, said frame comprising side and end plates and legs for supporting said frame above the floor of said inclosure, piping for supplying air to said fuel, said piping being disposed adjacent the bottom of said frame and baffle plates for directing the supplied air toward 60 65 said fuel.

9. A smoke generator for smoking meats, comprising in combination with a suitable inclosure, of a frame for containing the fuel 70 having side and end plates, legs supporting said frame above the bottom of the floor of said inclosure, said frame having an open bottom; oppositely disposed piping for supplying gas for preliminarily igniting the 75 fuel, oppositely disposed piping for supplying air to the fuel and a canopy positioned above said frame.

10. A smoke generator for smoking meats comprising an inclosure, a frame for containing the fuel, a canopy disposed above 80 said frame, means for pivoting said canopy and counterweight means for said canopy.

In testimony whereof I have signed this specification this first day of November, 85 1917.

ISAAC POWERS.
